UNITED STATES PATENT OFFICE.

JULIUS O. ROBERTS AND LESLIE V. WINTER, OF ABILENE, KANSAS.

STEAMER.

Application filed March 8, 1922. Serial No. 542,177.

To all whom it may concern:

Be it known that we, JULIUS O. ROBERTS and LESLIE V. WINTER, citizens of the United States, residing at Abilene, in the 5 county of Dickinson and State of Kansas, have invented a new and useful Steamer, of which the following is a specification.

This invention relates to devices especially designed in use for repairing storage batteries or the like, the primary object of the 10 invention being to provide a device of this character for steaming the storage battery for the purpose of loosening the seal of paraffin, or other sealing medium, to enable 15 the cells to be removed with facility.

Another object of the invention is to provide a device of this character which may be positioned over the upper portion of the 20 battery to direct the steam to the upper surface of the storage battery, eliminating the necessity of chopping or breaking the paraffin or sealing medium, to release the cells.

With the foregoing and other objects in view which will appear as the description 25 proceeds, the invention resides in the combination and arrangement of parts and in the details of construction hereinafter described and claimed, it being understood that changes in the precise embodiment of the 30 invention herein disclosed, may be made within the scope of what is claimed, without departing from the spirit of the invention.

Referring to the drawing:

Figure 1 is an elevational view of a battery 35 disclosing a device constructed in accordance with the present invention, as applied thereto, the device being shown in section.

Figure 2 is a bottom plan view of the device.

Referring to the drawing in detail, for the sake of illustration, a battery is indicated at 5, over which battery the device, forming the subject matter of this application 45 is shown as positioned.

The device comprises a hood embodying downwardly extending flanges 6 adapted to embrace the outer walls of a battery to be steamed. The upper walls of the hood are 50 inclined as at 7, to direct the steam to the upper surface of the battery. A pipe 8 is formed integral with the upper walls of

the hood 7 and is disposed centrally thereof, which pipe provides means for attaching the flexible pipe 9 to the battery, the pipe 55 9 being constructed to fit directly over the pipe 8 in a manner to prevent escapement of steam between the pipes 8 and 9. A suitable source of steam supply may be in communication with the hood 7 through the 60 pipes 8 and 9 and controlled by a suitable valve member not shown, so that when steam is admitted to the hood 7, the same will contact directly with the paraffin or sealing medium employed for sealing the cells 65 of the battery.

It will be seen that the hood 7 may be readily and easily removed permitting an operator to determine when the sealing medium has become sufficiently soft to release 70 the cells, whereupon the cells may be removed from the casing with efficiency, obviating all possibility of breaking the cells.

It might be further stated that the hood 75 7 is of such a construction that the upper surface of the hood contacts with the handles 10 forming a part of the usual battery construction, whereby movement of the hood with respect to the battery, is restricted, to 80 the end that a compartment is formed between the hood and upper surface of the battery to accommodate the steam.

Having thus described the invention, what is claimed as new is:-

In a device of the character described, a hood including an inclined upper wall, substantially wide flanges formed integral with the upper wall and extending downwardly therefrom, a pipe formed centrally 90 of the upper wall, to receive one end of a supply pipe, and said hood adapted to be positioned over a battery, the upper wall of the hood adapted to engage the handles of the battery to support the upper 95 wall in spaced relation therewith.

In testimony that we claim the foregoing as our own, we have hereto affixed our signatures in the presence of two witnesses.

JULIUS O. ROBERTS.
LESLIE V. WINTER.

Witnesses:

AUGUST SCHMITZ,
C. BONDEMAN.
